LEG WARMER BAG

Gertrude C. Williams, Cleveland, Ohio

Application October 28, 1946, Serial No. 706,179

6 Claims. (Cl. 2—69)

1

My present invention comprises a novel form of waterproof leg warming garment particularly adapted for use by persons sitting outdoors in cold weather, as for instance at football games, by riders of vehicles exposed to the cold when operating the vehicle, and for any similar uses.

One of the objects of my invention has been to produce a garment or covering of the type referred to which is preformed to fit the leg portions of a person when in sitting position, as distinguished from coverings for the same purpose in the prior art which are largely in the forms of bags that become wrinkled beneath the knee portions of the legs when the person wearing the covering sits down.

Still another object of my invention has been to produce a garment or leg covering of the class mentioned which comprises an outer layer of cover material of rubber or rubberized fabric, suitably combined with a layer or layers of warm fabric such as wool or blanket material, so that my article is impervious to water and therefore can be used out in the rain.

Still another object of my invention has been to provide novel fastening means for closing the leg warming sections of the garment or covering article after the same has been stepped into or pulled over the legs of the user or wearer, in conjunction with special fastening means for preventing displacement or sliding down of the thigh section of the covering from the thigh portions of the body, the last mentioned means being in the nature of a fastening belt part.

Still another feature of my construction of leg covering or garment lies in the provision of a foot rest member made of wood or similar insulative material of any suitable nature, the same being combined with the lower most or foot portion of the tibial section of my covering by fastening means connecting the same to a base rubber pad vulcanized to the rubber covering portion of the covering garment, the mode of connection reinforcing the lower or closed end or foot section of the garment in a manner that will be more fully understood upon reference to the following detailed description of my invention.

In the accompanying drawings forming a part of this specification,

Figure 1 is a vertical sectional view of a leg covering or garment embodying the construction of my invention.

Figure 2 is a front elevation of the garment as when in use upon the person, dotted lines illustrating the upper portion of the body of the person about whose legs the garment is fitted.

2

Figure 3 is a side elevation showing the garment as exhibited and applied to the person in Figure 2, the view bringing out clearly the manner in which the holding belt part is fitted around the back of the person wearing or using the garment or leg covering.

Describing my invention in detail and referring particularly to Figure 1 of the drawings it will be noted that the leg covering or garment of my invention comprises primarily an approximately vertical leg section A to which I shall refer hereafter as the tibial section, and the approximately horizontal section B which is the thigh or femur section of the garment. These sections A and B are formed integrally with one another and are pre-shaped in order to maintain the relation of approximate verticality of the section A in relation to the section B. The covering article of my invention is made up of an outer layer of material designated 1 which will preferably be made of rubber or rubberized water impervious material within which is provided the inner warming layer of material designated 2 which may be of wool or any known layer substance having warming characteristics or such as will assist in insulating the legs disposed in the garment from the outer atmosphere acting in conjunction with the outer covering layer of rubber or rubberized material designated 1.

The lower end of the tibial section A of my garment is closed and the upper end communicates of course with the thigh section B by way of a substantially continuous passage and the thigh section B is open rearwardly as indicated at 3 to permit entry of the legs of the wearer into the covering article in an obvious manner.

For facilitating the entry of the legs of a person into the garment at at least one side of the garment, the latter is slit along the tibial section A vertically and along the thigh section B approximately horizontally and the slit portions are adapted to be separated or untied by means of a common type of zipper or equivalent fastening means designated 4.

At its lower portion and internally thereof the tibial section A of my garment is provided with a foot rest block 5 made of wood or equivalent insulating material and this member 5 engages over the lower closed end portion of the rubber covering material 1 at the bottom.

On the under side of the bottom portion 6 of the rubber covering 1 is disposed a rubber section or block 7 of a thickness of approximately 55 1 inch in the actual article made according to my

invention. This rubber section is vulcanized to the rubber covering 1 adjacent thereto and the block 5 which is provided with an upwardly and forwardly inclined surface is attached to the lower end of the covering 1 and the member 7 by suitable fastening such as staples 8 driven into the block 5 from the bottom and effectively connecting the parts 5, 6, and 7 as well as providing a uniting of these parts to reinforce the covering 1 and the inner warming material section 2 in an effective manner.

The block 5 provides a very easy rest for the feet of the user of the garment or covering of my invention, prevents possibility of kicking through the bottom portion of the tibial section A of my article when introducing the feet and legs into the covering and also assists in maintaining the feet warm as the covering garment is being used.

As a means for preventing slipping forwardly and downwardly of the thigh section B of the covering, I may employ preferably a belt member 9 attached at one end to the right side portion of the section B at the open end of the latter adapted to pass around the back portion of the wearer, and to be buckled at its free end to the left lower side portion B below the zipper or equivalent fastening 4. By tightening the belt member 9 the upper or thigh section B of the covering can be pulled more easily over the thigh portions of the wearer, in an obvious manner.

It will be clear from Figures 2 and 3 that if desired the user or wearer of my covering garment may readily house his hands in the thigh section as well as the leg portions of his body and in introducing his hands into the covering the thigh section B need not be displaced if it is properly attached by the belt 9 to the body of the wearer.

The manner of use of my invention being readily made clear upon reference to my drawings and foregoing description, it suffices to state that my leg covering may be very quickly applied to the legs when the zipper or fastening 4 is released by moving the slider thereof to the lower end of the run of the slit portion of the garment. With the legs inserted so that the feet of the user rest upon the block 5, the garment will adapt itself to the disposition of the legs when the person is sitting, may be quickly fastened by means of the fastening 4 around the legs and then by tightening up the belt 9 at the buckle side of the garment the latter is ready for use.

Leg coverings of my construction as above set forth may be advantageously used by persons on voyages for keeping the legs warm while sitting out on deck when the weather is cold; in fact there are many uses for an article of the class set forth to which I have not referred herein.

The portions 1 and 2 of the garment may be united by adhesion or any suitable method of uniting similar layers of material known to the art.

It should be noted that the garment of my invention is additionally characterized by the fact that the legs and thighs of the wearer fit snugly from the bottom to the top. For this purpose the garment of my invention tapers gradually from a narrower diameter at the bottom to a wider diameter at the top in conformance respectively with the narrower diameter required to fit around the legs of the wearer and the wider diameter of the garment required to fit snugly around the thighs of the wearer.

Having thus described my invention, what I

claim as new and desire to secure by Letters Patent of the United States is:

1. As a new article of manufacture, a leg warming garment comprising a leg covering made of pre-shaped integral tibial and thigh leg sections normally disposed at an angle to each other conforming with the angle of the tibial portions and thighs of the legs of a person when sitting, and means to fasten the covering about the legs of a wearer, the sections including an outer layer of water impervious material, and an inner layer of warming material of the nature of wool united to the outer layer, the lower end of the tibial section being closed, a foot rest block of wood attached to the closed lower end of the tibial section inwardly thereof, and a rubber pad or section vulcanized to the outer under face of the impervious layer at the closed end of the tibial section.

2. As a new article of manufacture, a leg warming garment comprising a leg covering made of pre-shaped integral tibial and thigh leg sections normally disposed at an angle to each other conforming with the angle of the tibial portions and thighs of the legs of a person when sitting, and means to fasten the covering about the legs of a wearer, the sections including an outer layer of water impervious material, and an inner layer of warming material of the nature of wool united to the outer layer, the lower end of the tibial section being closed, a foot rest block of wood attached to the closed lower end of the tibial section inwardly thereof, and a rubber pad or section vulcanized to the outer under face of the impervious layer at the closed end of the tibial section and fastenings connecting the rubber pad with the block, said block and pad clamping the closed lower end of the tibial section therebetween.

3. As a new article of manufacture, a leg warming garment adapted to receive the legs and thigh portions of a wearer, said garment comprising an outer layer of water impervious material and an inner layer of warming material of the nature of wool united to the outer layer, said garment being closed at its lower end and open at the upper end and tapering from a relatively narrower diameter at the lower end to a relatively wider diameter at the upper end conforming to the requirements of snug fitting of the garment to the legs and thighs of the wearer combined with a foot rest block of insulating material attached to the closed lower end of the garment inside thereof, and a rubber pad or section vulcanized to the outer under face of the impervious layer at the closed end of the garment and beneath said block.

4. As a new article of manufacture, a leg warming garment adapted to receive the legs and thigh portions of a wearer, said garment being closed at one end and open at the other end, a foot rest block of insulating material attached to the closed end of the garment inside thereof, and a rubber pad or section secured to the outer under face of the garment at the closed end thereof and beneath said block.

5. As a new article of manufacture, a leg warming garment adapted to receive the legs and thigh portions of a wearer, said garment being closed at one end and open at the other end, a foot rest block of insulating material attached to the closed lower end of the garment inside thereof, a rubber pad or section secured to the outer under face of the garment at the closed end thereof and beneath said block, and fastenings connecting the

rubber pad with the block, said block and pad clamping the closed lower end of the garment therebetween.

6. As a new article of manufacture, a leg warming garment adapted to receive the legs and thigh portions of a wearer, said garment being closed at one end and open at the other end, and a foot rest block of insulating material attached to the closed end of the garment inside thereof, a rubber pad or section secured to the outer under face of the garment at the closed end thereof and beneath said block, and a belt member secured to the garment, at one side adjacent the open end thereof, and adjustably connected at the other end to the garment at the other side, 15 the belt member being secured to the garment

5

in such a manner as to extend from its point of attachment thereto toward the open end thereof, and adapted to extend around and engage the back of the wearer.
